UNITED STATES PATENT OFFICE.

FRANK WESLEY BULL AND WILLIAM OLIVER DURRANT, OF OSHAWA, ONTARIO, CANADA.

SHOCK ABSORBER.

Application filed April 9, 1923. Serial No. 630,996.

To all whom it may concern:

Be it known that we, FRANK WESLEY BULL and WILLIAM OLIVER DURRANT, both subjects of the King of Great Britain, and both residents of the town of Oshawa, in the county of Ontario, in the Province of Ontario, Canada, have jointly invented certain new and useful Improvements in Shock Absorbers, of which the following is the specification.

Our invention relates to improvements in shock absorbers and the object of the invention is to devise means whereby the action movement is a free movement and the reaction movement of the mechanism after impact is a controlled and cushioned movement so as to be gradual whereby the force of the rebound is completely absorbed or neutralized during such movement and at the same time devise such a mechanism as will be quick in action so that a series of successive action and reaction movements may be rapidly performed so that each individual reaction will be completely absorbed and it consists essentially of the arrangement and construction of parts as hereinafter more particularly explained by the following specification.

Fig. 1 is a rear elevation of a portion of an automobile showing the rear axle, rear wheel, spring and chassis frame and our device applied thereto.

Fig. 2 is a plan view of the parts shown in Fig. 1.

Fig. 3 is a sectional view through our device showing the parts in the position they assume after impact.

Fig. 4 is a sectional view on line 4—4, Fig. 3.

Fig. 5 is a similar view to Fig. 4 taken on line 5—5, Fig. 3 with the parts in the position they assume normally.

Fig. 6 is a plan view of our device showing the casing and outer parts in section, the parts being in the position they assume in Fig. 3.

Figs. 7 and 8 are perspective details of the outer and inner threaded members separated apart.

Fig. 9 is a perspective view of the members shown in Fig. 8 looking towards the opposite end.

Fig. 10 is a perspective detail showing the

means for connecting the cable to the axle of the automobile.

Fig. 11 is a detail view showing the means for connecting the cable to the casing of our shock absorber.

In the drawings like characters of reference indicate corresponding parts in each figure.

1 indicates the rear axle, 2 the rear wheel and 3 the usual spring by which the chassis frame 4 is supported upon the axle 1. The chassis frame 4 is channel-shaped according to common practice. 5 is a bracket secured by bolts 6 within the chassis frame so as to depend therefrom in a downwardly curved direction as indicated at 7. The lower end of the bracket 5 is provided with a circular recess 8 in its inner face centrally from which extends an orifice 9 through the bracket to the outer face thereof. 10 and 11 are diametrically opposite recesses formed in the base of the recess 8 and at diametrically opposite sides of the orifice 9. 12 is a stationary sleeve provided with a closed end 13 in which is formed a central orifice 14 at diametrically opposite sides of which are located projections 15 and 16. The end of the sleeve 12 having the closure 13 fits within the recess 8 and the projections 15 and 16 fit within the recesses 10 and 11 so as to hold the sleeve 12 in a stationary position preventing its rotation.

When in this position the orifice 14 of the sleeve 12 is in alignment with the orifice 9 of the bracket 5. 17 is a bolt which extends through the orifice 9 of the bracket 5 and the orifice 14 of the sleeve 12. The bolt 17 is provided with a surrounding collar or enlargement 18 fitting against the inner face of the end closure 13 of the sleeve 12. The outer end of the bolt 17 is threaded and projects to the outside of the bracket 5 and is provided with a securing nut 19 by which the bolt 17 is securely held in position. The bolt 17 extends centrally through the sleeve 12 projecting through the open end thereof to form a support for the moving parts of our mechanism.

20 is a casing, the body 21 of which is in the form of a sleeve which fits freely around the sleeve 12 at one end as clearly indicated in Figs. 4, 5 and 6. From the sleeve portion of the casing 20 extends a hollow quad-

rant-shaped portion 22 from the periphery of which extends a further extension 23 forming an arc-shaped rib in the periphery of which is formed a groove 24. In the face of the extension 23 is formed a groove 25 from one end of which extends an orifice 26.

27 is a cable which passes at one end through the orifice 26 into the groove 25. 10 Lead or other suitable metal is poured in a molten state into the groove 25 so as to surround the inner end of the cable 27 and securely hold it from withdrawal through the orifice 26. 28 is a lug extending from 15 the closure of the brake drum 29 of the wheel 2 (see Fig. 1). 30 is a bolt extending through such lug. 31 is a clip which is bent 20 so as to form a sleeve-like portion 32 through which the opposite end of the cable 27 extends.

From each side of the split of the sleeve 32 depend wings 33 and 34 (see Fig. 10) in which are formed aligned orifices 35 through which the bolt 30 extends. 36 is 25 a tightening nut which is screwed onto the bolt 30 so as to draw the wings 33 and 34 together and thereby contract the sleeve 32 to form a frictional grip on the cable 27 and thereby securely hold it in 30 place. The sleeve 12 is provided with internal ribs 12^x and 12°, the corresponding edges 13^x and 13° of which extend in a spiral direction, that is to say, in the form of a thread. 37 is an inner sleeve provided with 35 ribs 38 and 39, the opposite edges of which are also formed spiral as indicated at 38^x and 39°, the spiral of the ribs 38 and 39 conforming to the spirals 13^x and 13° with which they engage.

40 and 40^x are arms extending outward from the sleeve 37. The casing 20 hereinbefore referred to is divided into two portions 20^x and 20°. The portion 20° is in the form of a short sleeve from which extends 45 a quadrant-shaped flange 41 forming a closure for one end of the quadrant-shaped extension 22. The members 20^x and 20° are secured together by bolts 42 and 43. The bolts 42 and 43 also serve as bearing supports for the arms 40 and 40^x so as to reduce 50 the frictional contact of the arm 40 as it moves laterally as will hereinafter be explained.

44 is a compression spring surrounding 55 the bolt 17 between the outer end of the sleeve 37 and the outer end of the casing member 20°. 45 is a washer which forms a closure for the outer end of the casing member 20°, the bolt 17 extending through the 60 centre of the washer and being provided with a securing nut 46 bearing against the washer 45. The parts are normally in the position shown in Fig. 1, that is to say, with the quadrant extension 42 drawn 65 downward so as to compress the spring 44.

as indicated in Figures 5 and 6, the sleeve 37 being carried longitudinally outward upon the bolt 17 against the pressure of the spring 44 by the coaction of the internal thread or spiral ribs of the sleeve 12 and 70 the corresponding ribs 38 and 39 of the sleeve 37.

When the car strikes an obstruction or rut in the road causing a jolt the axle 1 and the chassis frame 4 are carried into close 75 juxtaposition compressing the spring 3.

Simultaneously the pull on the cable 27 is relieved permitting the extension 22 to swing upward, the casing being carried into this position by the spring 44, which, in expanding, forces the sleeve 37 longitudinally 80 inward into the sleeve 12, the engaging spiral ribs thereof causing the sleeve 37 to rotate and swing the arm 40 upward and the arm 40^x downward thereby carrying the casing 85 to the position shown in Fig. 3.

When the rebound occurs the axle 1 and chassis frame draw apart exerting a pull upon the cable 27 so as to again swing the extension 22 downward towards the position shown in Fig. 1, and thereby carry the arms 40 and 40^x circumferentially which, by such movement, rotates the sleeve 37 in the opposite direction to that above described so that the spiral engaging ribs of 95 the sleeves 37 and 12 carry the sleeve 37 longitudinally outward upon the bolts 17, the spring 44 opposing this movement.

It will be noted that when the sleeve 37 is turned within the sleeve 12 that a very 100 slight pressure upon the arm 40 serves to hold the arm in the adjusted position and therefore the action of the rebound will continue to be absorbed by the spring 44 until it is entirely neutralized, the opposing pressure of the spring 44 of course gradually increasing as it is compressed.

From this description it will be seen that we have devised a very simple form of shock absorber composed, first, of a stationary unit comprising the bracket 5, internally threaded sleeve 12 which may be detachably connected to the bracket or form an integral part thereof and the bolt 17 forming a supporting stud and second, of a movable unit comprising the casing 20 110 swung upon the bolt 17 and sleeve 12, an externally threaded sleeve engaged by the casing to coact with the thread of the sleeve 12 and the spring 44 opposing the reaction 120 movement of the sleeve 37. Also it will be seen that we have devised a shock absorber having a free movement during the shock action and a controlled or cushioned 125 movement during the reaction after each shock action and thereby entirely absorbing the rebound and eliminating the usual jar and tendency for the vehicle springs to be broken.

It will of course be understood that a 130

shock absorber is mounted upon each side of the frame and a flexible connection 27 extends outward and downward to the point of attachment at the end of the axle of the automobile.

It will thus be seen that the connections 27 at each side of the car diverge producing a lateral draw which neutralizes the swaying movement of the frame when subject to 10 shock and is therefore particularly adapted to a construction similar to Ford cars in which the carrying spring of the frame is mounted upon the axle and extends longitudinally thereof.

15 What we claim as our invention is:

1. In a shock absorber, the combination with the vehicle frame, axle and carrying springs interposed therebetween, of an internally threaded member carried by the frame, a casing turnably mounted upon the internally threaded member and held from horizontal movement, a flexible connection between the casing and the axle whereby the casing is rotated by the vertical movement of the vehicle frame in relation to the axle, an externally threaded member engaging the internal thread of the internally threaded member to move longitudinally therewith, an engaging connection between the casing and the externally threaded member adapted to permit the free inward horizontal movement of such member independent of the casing, and a normally compressed spring extending between the outer end of the externally threaded member and the opposing end of the casing.
2. In a shock absorber, the combination with the vehicle frame, axle and carrying springs interposed therebetween, of an internally threaded member carried by the

frame, a casing turnably mounted upon the internally threaded member, a flexible connection between the casing and the axle whereby the casing is rotated by the vertical movement of the vehicle frame in relation to the axle, an externally threaded member engaging the internal thread of the sleeve to move longitudinally therewith, a peripheral projection extending from the externally threaded member, and a bearing 50 piece carried by the casing parallel to the axis of the externally threaded member to form bearing contact with the projection when the casing is turned, and a normally compressed spring extending between the 55 outer end of the externally threaded member and the casing.

3. In a shock absorber, the combination with a vehicle frame, axle and carrier spring interposed therebetween, of a stationary internally threaded sleeve member carried by the frame, a stud bolt extending longitudinally therethrough, an externally threaded internal sleeve member coacting with the stationary sleeve and slidable upon the stud 60 bolt, a casing comprising a sleeve portion turnably mounted upon the stationary sleeve member and a quadrant portion forming an extension thereto, a compression spring surrounding the stud bolt between 65 the outer end of the internal member and the opposing end of the casing, an arm extending from the inner sleeve member bearing against an abutment formed in the casing, and a cable connection secured at one 70 end to the quadrant portion of the casing to engage the periphery thereof and at the opposite end to the axle.

FRANK WESLEY BULL.
WILLIAM OLIVER DURRANT.
